RAZOR BLADE ENVELOPE

Georges Monnet, New York, N. Y., assignor to
 Guardian Merchandising Corporation, Montreal, Quebec, Canada, a corporation of Quebec, Canada

Application August 28, 1941, Serial No. 408,565

1 Claim. (Cl. 206—46)

This invention relates to wrappers or envelopes for razor blades.

Safety razor blades are now packed individually in oiled paper and enclosed in paper envelopes. Practical experience has shown that this method of wrapping razor blades does not prevent the sharp edges thereof from rubbing against the paper wrapping so that in many instances the sharp edges of a razor blade are dulled even before the user removes the blade from its wrapping for the first time.

In my co-pending patent application, Serial Number 221,296, filed July 26, 1938, I proposed to eliminate this drawback through the provision of an envelope having cushion-like edge portions enclosing the sharp edges of the blade.

An object of the present invention is to improve a razor blade wrapper of this type by the provision of means preventing any possibility of rubbing or contact between the sharp edges of a razor blade and the wrapper.

Other objects of the present invention will become apparent in the course of the following specification.

The objects of the present invention may be realized through the provision of a razor blade wrapper having outstanding edge portions extending around the cutting edges of the blade, said wrapper also having blade holding means extending through the wrapper and the blade or engaging the blade to maintain it in a position in which its cutting edges will be protected by the outstanding edge portions of the wrapper and will be located at a proper distance from the inner surfaces of these edge portions.

The invention will appear more clearly from the following detailed description when taken in connection with the accompanying drawing showing, by way of example, preferred embodiments of the inventive idea.

In the drawing:

Figure 1 is a perspective view of a wrapper enclosing a blade.

Figure 2 shows the wrapper when it is open.

Figure 3 is a section along the line 3—3 of Figure 1.

Figure 4 is a perspective view of a somewhat different wrapper.

Figure 5 illustrates another wrapper in a perspective view.

Figure 6 shows yet another wrapper in a perspective view.

Figure 7 is a section along the line 7—7 of Figure 6.

The envelope 10 shown in Figures 1, 2 and 3

may consist of heavy paper or thin cardboard, or any other suitable material; it comprises a central portion 11 supporting a blade 12, lateral flaps 13 and 14 and front flaps 15 and 16 which are narrower than the lateral flaps 13 and 14. The outer front flap 16 is provided with a bent tongue 17 which facilitates the opening of the envelope.

The lateral flap 13 is bent along two lines 18 and 19 in relation to the central surface 11, thereby forming a thin side wall 20 extending at a distance from the cutting edge 21 of the blade 12. The lateral flap 14 is similarly bent along two lines 22 and 23 forming a side wall 24 which extends at a distance from the cutting edge 25 of the blade 12.

As shown in Figure 1, the surfaces of the envelope adjacent to the side walls 20 and 24 are, preferably, slightly bent, so that these surfaces converge in the directions toward the middle of the envelope, thereby forming pockets which enclose the cutting edges 21 and 25 of the blade and the inner surfaces of which surround the cutting edges without contacting them.

In the folded position of the envelope, the lateral flap 13 extends over the razor blade 12, the lateral flap 14 is placed over the flap 13, the inner front flap 15 extends over the flap 14 and transversely thereto, while the outer front flap 16 is placed over the flap 15 and is provided with a protruding tongue 17 to facilitate the opening of the envelope.

In accordance with the present invention, the blade 12 is held in the proper position within the envelope 10 by a clamp or clip 26. The clip 26 prevents the blade from shifting within the envelope and maintains its cutting edges 21 and 25 in air pockets enclosed by the lateral walls 20 and 24 and the adjacent surfaces of the envelope.

Preferably, the clip 26 consists of a piece of bent wire and may be similar to the clamps, clips or staples used for joining sheets of paper, paper matches and the like. The clip 26 has a front portion 27 extending over the upper flap 16, and two legs 28 and 29 extending at right angles to the portion 27 and passing through openings formed in the upper front flap 16, the lower front flap 15, the lateral flaps 14 and 13 and through the central opening 30 of the razor blade 12. The diameter of the wire clip 26 is so selected, that its legs 28 and 29 conveniently pass through the central opening 30 of the blade; they may engage the sides of the central opening 30 or they may be smaller than the width of that opening.

In the latter case, the pressure exerted by the clip 26 suffices to hold the blade 12 in place within the envelope. The legs 28 and 29 of the clip extend through the central supporting portion 11 of the envelope and have bent ends 31 and 32 extending toward each other and engaging the outer surface of the central portion 11.

The folded blade carrying envelope 10 provided with the clip 26 will effectively protect the blade contained therein and will prevent the sharp edges of the blade from being dulled by contact with the surfaces of the envelope. The blade may be conveniently removed from the envelope, since the flaps 16, 15, 14 and 13 may be easily torn off the clip 26, whereupon the blade 12 will be easily disengaged from the clip.

The envelope 40 shown in Figure 4 is provided with raised portions 41 and 42 extending along edges separating the lateral flaps of the envelope from its central or middle portion which carries the blade. The folds of the envelope extend substantially through the middle of the raised portions 41 and 42, so that air cushions are formed which completely surround the sharp edges of the blade and prevent them from contacting the envelope. Two elongated front flaps or tongues 43 and 44 are situated on opposite sides of the central blade-supporting portion of the envelope and are placed over the lateral flaps of the envelope and one over the other when the envelope is folded. The upper flap 44 is glued to the lower flap 43, and is provided with a bent tongue 45. This construction is substantially similar to that described in my aforesaid patent application.

A razor blade 12 is firmly held in its proper position within the envelope 40 by two clips 46 and 47 which embrace the shoulders 48 and 49 of the razor blade. The clip 46 has a central portion extending over the upper surface of the flap 44 and two inwardly bent legs passing through openings formed in the flap 44 and the lateral flaps and on both sides of the shoulder 48 of the razor blade. These legs extend through the central portion of the envelope and are bent inwardly over the outer surface of this central portion. Similarly, the clip 46 extends over the flap 43 and has legs passing through this flap 44 and the lateral flaps and on both sides of the shoulder 49 of the blade, these legs extending through the central portion of the envelope and being bent inwardly over the outer surface of the central portion.

Thus the razor blade is firmly held within the envelope 40 either by direct contact with the legs of the clip 46 and 47, or by pressure exerted by the two clips upon the shoulder portions 48 and 49 of the razor blades.

The envelope 50 shown in Figure 5 is substantially similar to the envelope 40 in Figure 4 and includes raised portions 51 and 52 and flaps 53 and 54. In this construction, a razor blade is

firmly held in the required position within the envelope 50 by two eyelets 55 and 56 made of metal or the like and having the form of sleeves extending through the flaps, the central opening 30 of a razor blade 12 and through the central supporting portion of the envelope; the sleeves have flanges extending over the underlying surfaces of the envelope, so that the blade is clamped by the eyelets 55 and 56.

The envelope 60 shown in Figures 6 and 7 includes a central portion 61 supporting a blade 12 and lateral flaps 62 and 63 which do not overlap each other, but terminate at a distance from one another. Two raised portions 64 and 65 extend along the edges separating the flaps 62 and 63, respectively, from the middle portion 61, the fold of the envelope extending substantially through the middle of the raised portions. Two front flaps or tongues 66 and 67 are placed over the adjoining edges of the flaps 62 and 63 when the envelope is folded.

The blade 12 is held in place within the envelope 60 by flaps 68 and 69 which extend through a central opening 70 formed in the flaps 66 and 67 and the middle portion 61. The opening 70 is situated above and below the central opening 30 of the razor blade 12 and may be in alignment with the opening 30. The adjacent edges of the lateral flaps 62 and 63 are situated on both sides of the opening 70. The flaps 68 and 69 are integral with or firmly joined to the central portion 61 of the envelope; they extend through the opening 70 of the envelope and the opening 30 of the razor blade and are bent outwardly over the adjacent edges of the flap 67. Thus the flaps 68 and 69 hold the blade 12 firmly in its required position within the envelope 60.

It is apparent that the specific illustrations shown above have been given by way of illustration and not by way of limitation, and that the structures above described are subject to wide variation and modification without departing from the scope or intent of the invention, all of which variations and modifications are to be included within the scope of the present invention.

What is claimed is:

A razor-blade envelope, comprising a blade-supporting portion, flaps for covering a blade carried by said blade-supporting portion and a metal clip having a middle portion extending over the uppermost of said flaps, and legs extending through openings formed in said flaps and said blade-supporting portion and through a central razor-engaging opening formed in said blade said clip being disposed in its entirety over said central razor-engaging opening, said legs having bent ends extending in opposite directions over the outer surface of said blade-supporting portion, whereby said blade is maintained in its position upon said blade-supporting portion.

GEORGES MONNET.
